Patwrite Law(57) **CLAIM**

The ornamental design for a toilet assistance device, as shown and described.

DESCRIPTION

FIG. 1 is a front view of a toilet assistance device showing my new design;

FIG. 2 is a right side view thereof, the left side view being a mirror image thereof;

FIG. 3 is a rear view thereof;

FIG. 4 is a top plan view thereof;

FIG. 5 is a bottom plan view thereof; and,

FIG. 6 is a perspective view thereof.

The broken lines depict environmental subject matter and form no part of the claimed design.
